UNITED STATES PATENT OFFICE.

CLYDE A. AUNGER, OF SAN FRANCISCO, CALIFORNIA.

ARTIFICIAL KNEE-JOINT.

1,138,923.

Specification of Letters Patent. Patented May 11, 1915.

Application filed May 13, 1913, Serial No. 767,718. Renewed October 12, 1914. Serial No. 888,418.

To all whom it may concern:

Be it known that I, CLYDE A. AUNGER, a citizen of the United States, and a resident of the city and county of San Francisco, State of California, have invented a new and useful Improvement in Artificial Knee-Joints, of which the following is a specification.

My invention relates to knee bolts and back checks for artificial limbs, wherein the knee bolt is pivotally mounted within the stump portion and is rigidly secured to the leg portion and is provided with a lateral member adapted to engage an adjustable stop for the purpose of limiting the forward movement of the said leg portion, and its objects are, first, to provide a back check secured to the leg portion and adapted to engage a stop within the stump portion 20 without having a slot in the said stump portion, second, to provide means which may be secured to the back check for the purpose of operating the leg portion, third, to provide a device of the character described 25 which shall be simple in construction, have few parts and one which may be adjusted without removing the artificial limb.

I accomplish these several features by means of the device illustrated in the drawings forming a part of the present specification, wherein like numerals of reference designate similar parts throughout the said drawings and specification and in which—

Figure 1 is a side elevation of an artificial limb showing the shoulder straps and the check strap, the lower portion of the leg being broken away. Fig. 2 is an enlarged vertical section showing the knee bolt, the back check secured thereto, the adjustable stop and the manner in which the lower end of the shoulder straps are secured to the back check.

Referring to the drawings, the numeral 1 is used to designate a leg portion having a rigid side bar 2 secured at each side of the upper end thereof. A knee bolt 3 is rigidly secured between the upper ends of the rigid side bar 2 and is provided with an arm 4 to which a roller 5 is secured. A stump portion 6 is rotatably mounted upon the bolt 3 and is provided with a lug 7 having a nut 8 secured to the lower end thereof. Within the lug 7 is a screw 9 which engages the nut 8 on the lower end of the lug 7. An opening 10 is provided in the front portion of the stump 6 for the adjustment of the

screw 9. A strap 12 passes over a roller 14 and through a slot 15 in the front portion of the stump 6, said strap also engaging the roller 5 on the arm 4 and from thence passing through a slot 16 and over a roller 17 in the back portion of the stump. The upper ends of the strap 12 are secured to the lower ends of the two shoulder straps 18. A strap check 20 encircles the upper portion of the stump 6 for the purpose of retaining the upper ends of the strap 12 adjacent to the stump 6.

We will assume for the purpose of illustration, that the artificial limb shown herein is attached to the stump of the right leg. While the body is being supported by the left leg in taking a step forward with the right leg, the right knee will first be brought forward which causes the leg portion 1 to move slightly backward, when the arm 4 moving with the knee bolt 3 of the leg 1 will swing away from the screw 9 until the leg portion 1 is clear of the ground. In stepping forward with the right leg a slight hitch of either shoulder will be communicated by means of the shoulder straps 18, strap 12 and pulley 5 to the arm 4 which is secured to the knee bolt 3, and cause the leg portion 1 to be brought forward until the end of the arm 4 engages the lower end of the screw 9, when the foot of the leg portion 1 is in a position to support the weight of the wearer and may be placed upon the ground.

When standing, the weight of the body being naturally slightly in advance of the knee bolt 3, the stump portion 6 will tend to rotate on the knee bolt 3 rigidly secured to the rigid side bar 2 of the leg portion 1, until the lower end of the screw 9 within the stump portion 6 engages the outer end of the arm 4.

The forward movement of the leg portion 1 may be adjusted by turning the screw 9, thereby causing the said screw to be extended beyond or receded within the supporting nut 8 secured to the lug 7 of the stump portion 6.

It is obvious from the foregoing that I have provided a simple and effective back check which may be adjusted without removing the artificial limb.

Having thus described my invention what I claim as new and desire to secure by Letters Patent is:—

1. An artificial knee joint comprising a leg portion having a knee bolt rigidly se-

- cured to the upper end thereof; a stump portion rotatably mounted upon the rigid knee bolt and having a lug on the inner side of the front portion thereof; an arm fixedly secured to the rigid knee bolt adapted to engage the lug on the stump portion; and means for moving the leg portion forward.
2. An artificial knee joint comprising a leg portion having a rigid side bar on each side of the upper portion thereof; a knee bolt rigidly secured between the upper ends of the rigid side bar; a lateral arm fixedly secured to the knee bolt; a stump portion rotatably mounted upon the rigid knee bolt and having a lug on the inner side of the front portion thereof adapted to engage the end of the arm secured to the rigid knee bolt; a roller secured to the upper surface of the arm; and means secured to the roller adapted to be operated by the shoulders of the wearer of the artificial knee joint for the purpose of bringing the leg portion forward.
3. An artificial knee joint comprising a hollow leg portion; a rigid side bar on each side of the upper end of the leg portion; a knee bolt rigidly secured between the upper ends of the rigid side bar; a lateral arm fixedly secured to the rigid knee bolt and having a roller secured to the upper surface thereof; a hollow stump portion having slots in the front and rear portion thereof; suitable shoulder straps passing through the said slots and engaging the roller on the upper surface of the arm; and means secured within the front portion of the stump and adapted to engage the end of the lateral arm secured to the rigid knee bolt.
4. An artificial knee joint comprising a hollow leg portion; a rigid side bar on each side of the upper end of the leg portion; a knee bolt rigidly secured between the upper ends of the rigid side bar; a lateral arm fixedly secured to the rigid knee bolt and having a roller secured to the upper surface thereof; a hollow stump portion having slots in the front and rear portion thereof; suitable shoulder straps passing through the said slots and engaging the roller on the upper surface of the arm; and adjustable means secured within the front portion of the stump and adapted to engage the end of the lateral arm secured to the rigid knee bolt.

5. An artificial knee joint comprising a hollow leg portion; a rigid side bar on each side of the upper end of the leg portion; a knee bolt rigidly secured between the upper ends of the rigid side bar; a lateral arm fixedly secured to the rigid knee bolt and having a roller secured to the upper surface thereof; a hollow stump portion having slots in the front and rear portion thereof; suitable shoulder straps passing through the said slots and engaging the roller on the upper surface of the arm; and adjustable means secured within the front portion of the stump and adapted to engage the end of the lateral arm secured to the rigid knee bolt.

6. An artificial knee joint comprising a hollow leg portion; a rigid side bar on each side of the upper end of the leg portion; a knee bolt rigidly secured between the upper ends of the rigid side bar; a lateral arm fixedly secured to the rigid knee bolt and having a roller secured to the upper surface thereof; a hollow stump portion having slots in the front and rear portion thereof; suitable shoulder straps passing through the said slots and engaging the roller on the upper surface of the arm; a nut secured to the inner side of the front wall of the stump portion; and a screw within the nut adapted to be adjusted from the outside of the stump portion and to engage the end of the arm secured to the knee bolt within the stump portion.

In witness whereof I hereunto set my signature in the presence of two subscribing witnesses.
